CLAIM

The ornamental design for a nose cleaning system, as shown and described.

DESCRIPTION

FIG. 1 is a front, right perspective view of a nose cleaning system showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right perspective view of the nose cleaning system with a cover.

The portions of the drawings illustrated in broken lines form no part of the claimed design
